A. C. MAGRATH

LINE BAR FOR CROSSBAR LINE SWITCHES

Filed Oct. 16, 1920

Inventor:
Arthur C. Magrath,
by Joel C. Palmer
Atty

UNITED STATES PATENT OFFICE.

ARTHUR C. MAGRATH, OF BROOKLYN, NEW YORK, ASSIGNOR TO WESTERN ELECTRIC COMPANY, INCORPORATED, OF NEW YORK, N. Y., A CORPORATION OF NEW YORK.

LINE BAR FOR CROSSBAR LINE SWITCHES.

Application filed October 16, 1920. Serial No. 417,428.

To all whom it may concern:

Be it known that I, ARTHUR C. MAGRATH, a citizen of the United States, residing at Brooklyn, in the county of Kings, State of

5 New York, have invented certain new and useful Improvements in Line Bars for Crossbar Line Switches, of which the following is a full, clear, concise, and exact description.

10 This invention relates to line switches of the cross bar type adapted for use in automatic telephone exchanges for establishing connections between subscribers' lines and trunk lines extending to first selector switches. More particularly, the invention relates to line bars for use in cross bar switches.

15 The present invention has for its object, the provision of a line bar which may be produced at a relatively low cost and which, at the same time, is thoroughly reliable in operation.

20 Line bars made in accordance with the present invention are characterized by the absence of any screws, bolts, rivets or the like, in their embodiment. Instead of employing such media, the various metal parts of the line bar are assembled together and held in their proper relationship by being firmly embedded in molded parts of insulating material.

25 The accompanying drawing shows a perspective view of an assembled line bar, some portions being shown in cross section. Parts 1, 2, 3 and 4 are flat metal conducting strips, each of which is provided with a plurality of lugs 5, the function of which is to make contact with terminals of the trunk bars which cooperate with these line bars to establish connections between subscribers' lines and trunk lines. The four conducting strips 1, 2, 3 and 4 are firmly embedded in and insulated from each other by blocks of insulating material 6, 7, 8 and 9. Also embedded in each of the end blocks 6 and 9 respectively is a supporting element in the form of a U-shaped clevis 10 which is provided with apertures 11 for engaging fulcrum pin 12.

30 The line bar is intended to be pivotally mounted on links 13 which in turn are piv-

otally mounted on brackets 14. Electromagnet 15 with its armature 16 is adapted to operate the line bar.

For a full description of the functions and method of operation of the line bar, reference may be had to Patent No. 1,462,047 of July 17, 1923, to J. N. Reynolds.

What is claimed is:

1. In combination, a plurality of parallel metallic strips, supporting elements therefor and a plurality of blocks of insulating material into which said strips and said supporting elements are embedded.

2. In combination, a plurality of conducting strips, supporting elements therefor and a plurality of insulating blocks for securing said elements on said strips.

3. In combination, a plurality of parallel and superposed metallic strips, a set of contacting lugs integrally formed with each of said strips, supporting elements therefor, and couplings of insulating material cast at the ends of said strips for securing said elements thereto.

4. A line bar comprising a plurality of parallel conducting strips, a molded insulator at each end of said line bar into which the ends of said conducting strips are embedded, and a U-shaped clevis embedded in each of said insulators, the extremities of said clevises projecting outwardly from said insulators.

5. A multiple electrical conductor comprising a plurality of parallel conductors having superposed contact positions, and a plurality of supports therefor comprising insulating blocks in each of which a plurality of said conductors is embedded.

6. A multiple electrical conductor comprising a plurality of parallel conductors, a plurality of supports therefor comprising insulating blocks in each of which a plurality of said conductors is embedded, and transversely aligned contact portions on said electrical conductors located between adjacent blocks.

In witness whereof, I hereunto subscribe my name this 14th day of October, A. D., 1920.

ARTHUR C. MAGRATH.
